UNITED STATES PATENT OFFICE.

FRANK H. LEHMAN, OF LEBANON, PENNSYLVANIA.

ASH-SIFTING DEVICE.

Application filed February 12, 1923. Serial No. 618,578.

To all whom it may concern:

Be it known that I, FRANK H. LEHMAN, a citizen of the United States, residing in the city of Lebanon, county of Lebanon, 5 and State of Pennsylvania, have invented certain new and useful Improvements in Ash-Sifting Devices, of which the following is a specification.

My invention relates to improvements in 10 ash sifting devices, and more especially to those adapted to be used in the household for sifting ashes drawn from stoves and furnaces.

In Letters Patent of the United States, 15 Numbers 1,401,543 and 1,403,469, issued to me December 27, 1921 and January 10, 1922, respectively, I have disclosed and claimed dustless ash sifting devices designed for use in conjunction with ash cans of the conventional cylindrical type, and in which the sifting of the ashes is accomplished through the rotation of a portable ash containing and sifting element having the general appearance and functions of a pail, in a mounting arranged in a dust proof closure fitting over and adapted to seal the mouth of the can.

The present invention is of an analogous character, but is directed toward the production of a cheaper device of this kind, and one which because of its appearance and relative simplicity of construction and operation will make a stronger appeal to the prospective purchaser; the principal elements of novelty residing in the economic and common form and the simple character of the ash containing and sifting element, the novel and economic can closure, and the relatively simple, efficient and cheaply made means employed for mounting, closing and rotating the element within the closure, as well as the manner of disposing the element in the mounting, the latter involving a nice and novel arrangement whereby a limited portion of the space of the can is sacrificed to the end of enabling the device to be very cheaply manufactured out of a minimum amount of material. Other objects and features of novelty will be apparent from the 50 description taken in connection with the accompanying drawings in which:—

Figure 1 is a central vertical sectional view of an embodiment of my invention, showing the portable ash sifting element 55 mounted in position for rotation in the hood.

Figure 2 is a front elevational view there-

of showing the lid turned to open position and supported on the edge of the can with the ash sifting element disposed in mounted position therein.

Figure 3 is a view similar to Fig. 2 showing the lid with the ash sifting element removed therefrom and the closure carrying cross arm in retained position on the catch.

Figure 4 is a side elevation of the invention as shown in Fig. 3 with the cross arm in remote depending position, parts of the lid being broken away to more clearly show the construction.

Figure 5 is an elevation, partly in section, of the portable ash containing and sifting element.

Figure 6 is a top view of said element with the closure thereon, the latter being shown as on line 6—6 of Fig. 2.

Figure 7 is a fragmentary view taken on line 7—7 of Fig. 3; Figure 8, a fragmentary view taken on line 8—8 of Fig. 3; and Figure 9 a fragmentary perspective view of the hinge member employed in connection with the cross arm.

Referring more particularly to the drawings, the ash containing and sifting element employed for carrying and separating the ashes, is constructed substantially in the form of an upwardly flaring bucket or pail 10 open at the top and having a closed imperforate bottom 12 and side walls 11, and provided with the usual bail 13 for carrying it about in upright position. In the present instance, for economy of construction, I preferably use for the outer member of the element a common commercial sheet metal pail such as shown in Fig. 5. These pails are at the present time very cheaply made in uniform styles and sizes and require but slight modification to render them available for the purposes of the invention. Furthermore, people in general are accustomed to seeing and handling pails of this kind, and by utilizing the same as the main or outer part of the sifting element, the manner of using and operating the sifter becomes more immediately apparent, and the instinctive prejudice against the use of the same as a novel utensil is largely overcome.

The sifting member of the element in the present improvement consists of a shell 14 of foraminous or reticulated material contained in spaced relation within the body of the pail, being secured therein by attachment of

the lower edge 15 thereof in any suitable manner either to the side walls 11, the bottom 12, or both the side walls and bottom at their juncture, as may be preferred. Said shell is preferably cylindrical in form, and is simply and cheaply made by rolling up a sheet of suitable material into a cylinder and securing together the meeting or opposite edges thereof. In the present instance, the shell is secured in the pail in such a manner that the open upper end or mouth 16 thereof, falls substantially concentrically within and slightly below the mouth 18 of the pail, with the edge 17 thereof in a plane substantially parallel with the plane of the mouth of the pail, thus preserving the common general outward appearance of the pail and affording complete protection for the shell against denting and distortion through impact with foreign objects with which the element may be brought into forcible contact either accidentally or otherwise, in the ordinary handling and manipulation of the device, while at the same time providing a construction which admits of the use of novel and efficient means for rotatively clamping and coupling the element in a mounting of the character hereinafter described.

30 The invention contemplates the employment of a portable containing element thus constructed in the capacity of a rotary sifter, whereby ashes deposited therein may be effectually sifted and separated, the valuable unconsumed portions thereof being conserved and retained in the element, while the finer consumed portions, which pass through the mesh of the shell, are ejected and discharged. For the purpose of thus using the element, and for the further purpose of readily mounting and adjusting it in appropriate operative position and rendering the sifting operation substantially dustless, I provide means for rotatively and detachably securing the element partially within and on the lower side of a lid 19 which is adapted to be removably seated on an ash can as 20, preferably of the conventional, cylindrical type, shown. The lid in the present instance is simply and cheaply made from a minimum amount of sheet metal by forming the same with a flat top or closure portion 21 adapted to rest over the mouth of the can, surrounding said flat portion with a peripheral depending flange 22, and erecting in the central or intermediate area thereof a closed hood 23, having a contour substantially similar to that of the half part of an axially divided frustrated cone, and substantially conforming with but being slightly larger than the half of the containing element, so that the latter may be freely and snugly received in the recess thereby formed on the lower or inner side of the lid and may be therein rotated on an axis sub-

stantially in the plane of the flat portion of the lid. As will be seen, the hood is entirely and completely closed, being formed with imperforate end walls 51 and 52, which, together with the arched wall 33 thereof are 70 made continuous with the surrounding flat portion of the lid, and thus form therewith an efficient dust proof closure for the ash can.

For removably and rotatively mounting 75 and supporting the sifting element in the desired position on the inner side of the lid, I employ adjustable rotative friction and closure clamping and locking means for engagement with the bottom and mouth of the element respectively, said means consisting of a manually rotative friction disk 24 adapted to enter the recess formed by the tine at the bottom of the pail, and a pivoted closure 25 of novel form and design for entering the mouth of the pail and closing the mouth of the sifting shell 14.

The friction disk 24 is mounted on the end of a short shaft 26 extending externally of the hood through a suitable perforation in the end wall 52 thereof and is journaled in bearing openings 27 provided in the opposite legs of an inverted U-shaped bearing bracket 28 secured to the end of the hood and to the flange 22 of the lid. Said shaft 95 terminates outwardly in a crank 29 whereby it is adapted to be rotated and the friction disk is secured to the inner end thereof in a simple manner as by the insertion of a pin 30 transversely through the body of the disk and the shaft, a suitable transverse opening (not shown), being provided in the shaft for this purpose. Washers or other suitable spacing devices as 31 are interposed on the shaft between the inner face of the 100 end wall of the hood and the disk to prevent contact therebetween and to permit slight angular play of the disk on the shaft. The closure 25 for engaging the opposite end or mouth of the element is centrally pivoted 105 for rotation at a suitable intermediate point on a cross arm 32 hinged on one side of the hood adjacent the juncture of the arched wall 33 thereof and the flat portion of the lid, and is thus adapted to be swung into 110 the hood recess by means of the arm and brought to appropriate central clamping and closing position over the element in the upper part of the hood. The closure, used in the present invention is designed to perform 115 three distinct functions, namely, that of co-operating with the friction disk in rotatively supporting the element; that of closing and sealing the mouth of the sifting shell 14 while permitting the siftings accumulating in the space intervening between the shell and the pail to pass forwardly thereof and drop from the mouth of the pail; and that of exerting, when in closed position on the element, upward or forward spring pres- 120

sure sufficient to retain the free end of the cross arm 32 in detachable locked engagement with a suitable keeper provided on the lid adjacent the side of the hood opposite 5 that to which the arm is hinged. To this end the closure is economically made in the form of a flat plate of suitable shape and outline to enter the mouth of the pail and completely cover the mouth of the shell 14 10 while substantially contacting the interior walls of the pail at a sufficient number of points to maintain the latter in concentric relation with the pivot 34 and permitting a considerable portion of the area of the space 15 intervening between the shell and the pail to remain open and uncovered for the passage of siftings. In the preferred form of the invention here shown, the plate is given a rectangular outline with the corners or angular portions thereof cut away, and is reinforced and stiffened by turning up its marginal edges 53 at right angles, although as will be obvious it may be given a variety of different shapes and forms, all falling 20 within the scope of the invention.

For hinging the cross arm 32 to the lid I provide on one end thereof a hinge pin 36 which is adapted to enter and be engaged by a knuckle 35 disposed on the flat portion 30 of the lid adjacent one side of the hood, and to be retained therein against lengthwise disengagement by a retaining head or finger 37. The opposite end of the arm is formed with a latch extension 38 adapted to pass 35 under and engage the hook like keeper 39 projecting from the opposite side of the hood. The cross arm is likewise provided with a heel 40 disposed substantially in axial alignment with the pivot 34 but on the 40 opposite side of a line passing through the hinge and the keeper, said heel being adapted to abut against the flat portion of the lid immediately above the hood recess to act with the hinge knuckle 35 in preventing 45 torsional or turning movement of the arm due to the weight of the element on the pivot, and to thus maintain the pivot in substantial alignment with the shaft 26, when the element is locked in horizontal position 50 within the lid.

Preferably the cross arm 32 is made by bending up a single length of suitable rod material into the form shown, an intermediate section of the rod being V-shaped and 55 formed with a central arcuate apex 54 adapted to lie closely against the upper face of a relatively thin bearing block 55 centrally disposed on the upper side of the closure 25 and to thus follow the closure into 60 the mouth of the element, while the diverging legs of the section extend outwardly and upwardly at an appropriate angle to permit the ears 56 of the pail to pass under and clear the terminal portions of the legs when 65 the arm is in locked position across the hood recess. One of the legs of the central section is then continued outwardly, downwardly and inwardly to form the hinge pin and its retaining finger, and the opposite leg is extended outwardly to form the latch 70 38 and thence continued upwardly, inwardly and downwardly across the apex 54 in a triangular loop to produce the heel 40 and the pivot 34. It will be noted that in this construction the portion of the rod extending from the heel to the pivot passes to the rear of and rests against the central section, and that the pivot is thus reinforced and supported and is adapted to be maintained 75 in proper alignment with the shaft 26 80 against the weight of the element, when the latter is mounted and locked in horizontal operative position within the lid. It will likewise be noted that the thrust of the element against the cross arm when in such operative position is completely taken up by the apex 54 of the central section, which latter forms a very simple and efficient bearing for this purpose. Since the closure may be retained on the pivot in any simple manner 85 as by means of a cotter pin as 46 inserted in a suitable transverse opening adjacent the end thereof, it will be apparent that the cross arm can be very economically produced in this manner, relatively few and simple 90 operations being required for its manufacture.

To avoid spilling the ashes while introducing and securing the ash containing element in the rotary means within the lid, it is obviously essential that the element be continuously carried and held in a substantially upright vertical position throughout the entire mounting operation, and it is one of the features of this invention to provide hinging and supporting means which enable the lid to be turned to and supported in an upright open position over the edge of the ash can, so that the operation of introducing and locking the element therein may be performed without the necessity of bodily lifting or removing the lid from the can.

The hinging and supporting means provided in the present invention for the accomplishment of this purpose comprise a 115 hook like downward or inward extension 41 of the inner leg of the U-shaped bearing bracket 28, a suitable opening being provided in the flat portion of the lid adjacent the end wall 52 of the hood for the passage 120 of the extension, and the terminal portion of the free end thereof being turned outwardly and slightly upwardly to form a bill 42 adapted to catch over the adjacent edge 125 of the can when the lid is turned to open position over the latter. As shown, the hook is spaced from the flange 22 of the lid, and the bill is disposed slightly below the lower edge of the flange, so that while the lid may be freely removed and again re- 130

placed on the mouth of the can by simply lifting the same vertically therefrom as by means of the handle 43, it is likewise adapted to be turned or swung over the edge of the can and to be retained thereon in upright or substantially vertical position by means of the hook, in which position it is readily accessible for the introduction and adjustment of the sifting element in the manner described.

To enable the closure 25 and its carrying cross-arm 32 to be swung aside sufficiently to allow the free introduction of the sifting element into the hood and permit the proper seating of the element on the friction disk 24, and in order to enable the closure to be raised upwardly over the element to a sufficient extent to clear the same when the cross arm is thus swung inwardly on its hinge, 15 seating of the element on the friction disk 24, and in order to enable the closure to be raised upwardly over the element to a sufficient extent to clear the same when the cross arm is thus swung inwardly on its hinge, 20 the hinge knuckle 35, which in the present instance is in the form of a hook attached as at 44 (see Fig. 9) to the inner wall of the hood, is so designed as to provide an upwardly diverging opening or channel 57 25 wherein the hinge pin 36 has both rotative and lateral play. The upper edge of the knuckle is further chamfered outwardly as at 58 to permit the cross arm to swing freely over the same in this movement, and 30 to enable the arm when in its extreme remote or outward position to hang downwardly and inwardly toward the lid thus bringing its weight relatively close in to the point where the lid is supported on the can. 35 It will be apparent that, with nothing further than the support afforded by the hook 41, the lid when in open position on the can would tend to be unstable, the center of gravity thereof being located a considerable 40 distance above the point of support, and the weight of the cross arm and closure being also above and to one side of the support. This tendency is somewhat overcome by forming the hinge knuckle 35 in the manner 45 described to bring the cross arm down relatively close to the lid, but in order to entirely obviate this tendency and insure the complete stability of the lid, I additionally supply a member adapted to co-operate with 50 the hook 41 in providing a relatively wide purchase or bearing for the lid on the edge of the can. This member consists in the present instance of a W-shaped clip 45 which is caught intermediately under the bill 42 of the hook and is provided with 55 arms 59 extending laterally on either side of the hook having their free ends 47 firmly attached to the lid adjacent the opposite sides of the lower end of the hood recess. This clip is preferably made of spring wire material and is of such shape and size that when its ends are thus attached to the lid and the intermediate portion is sprung under the bill of the hook, the latter assumes an arcuate shape falling inside and

following substantially the arc of the adjacent edge of the can, with the arms 59 thereof passing over the edge of the can at points sufficiently remote from the hook to entirely counteract any rotary tendency of the lid. 70

In operation the containing element is placed in a convenient position adjacent a stove or furnace from which it is desired to remove ashes, and there is filled from the ash pit in the usual manner, such portion of the ashes as pass through the sifting shell being caught and retained in the surrounding intermediate space within the pail. When thus filled the element is taken up by the bail and carried to the ash can in the same manner as an ordinary hod or bucket, there being no danger of spilling or dropping the ashes on the floor while carrying the same about. The lid 19 is now taken by the handle 43 and swung back on the hinge hook 41 over the edge of the can until the adjacent edge of the flange 22 abuts against the can when the lid will be in open upright position so that the element may readily be lifted into the hood and seated on the friction disk 24. The cross arm 32 is then swung upwardly and inwardly across the hood recess to carry the closure 25 over the mouth of the element, when with a slight downward and further inward movement and pressure on the free end of the arm the closure is inserted in the mouth of the element and the latch thrust home under the keeper; thus securely locking the element in operative rotary position. The lid is then returned to closed position over the can when the element will be in substantially horizontal position under the lid and may be rotated to sift the ashes by turning the crank 29, the crank imparting rotary movement to the friction disk 24, and the latter in turn transmitting such movement to the element through frictional contact with the bottom thereof. As will be understood the rotation of the element causes the finer consumed portion of the ashes to drop through the meshes of the shell 14 into the intervening space between the shell and the pail, whence due to the flaring of the pail, continued rotation thereof urges the material forward through the uncovered spaces in the mouth of the element and ejects the same therefrom. Since the sifting operation takes place entirely under the lid, it will be apparent that all dust arising therefrom is confined within the can. After the ashes have been thoroughly sifted, the apparatus is left to stand undisturbed a sufficient length of time to permit the dust to become completely settled, whereupon the lid is again opened and the element with the reclaimed cinders therein removed. 100

To prevent the cross arm 32 from hanging down in the can when the sifter is not 130

in use, I supply means for detachably retaining the free end of the arm normally in relatively close proximity to the lid, said means consisting of a reentrant notch 50 formed in the upper edge of the keeper 39 wherein a member of the arm as 61 is adapted to be loosely caught and held.

As will be obvious, since the lid rests loosely on the can, there being no connection 10 therebetween, the former may be readily lifted off whenever it is desired to empty or otherwise separately handle the can.

In this invention it should be observed, that when the sifting element is in mounted 15 position over the ash can approximately one-half portion thereof extends downwardly into the can, which arrangement while slightly limiting the capacity of the can, is an important economical factor in the production of the lid, since it enables the lid with a suitable enclosing hood thereon, to be made very cheaply from a minimum amount of material.

What I claim is:

25 1. A rotary ash sifting device, including a portable ash containing element comprising an outer imperforate receptacle in the form of a pail and an inner foraminous sifting receptacle in the form of a cup, the mouth of the outer receptacle being slightly above the mouth of the inner receptacle, and the walls of said receptacle being substantially spaced apart at the mouths thereof, to permit the free extrusion of ashes through 30 the intervening space.

2. A rotary ash sifting device, including a portable ash containing element comprising an outer imperforate receptacle and an inner foraminous sifting receptacle, said 40 receptacles being upwardly spaced apart and the same being closed and rigidly connected to each other at their lower ends and being open at their upper ends, the mouth of the outer receptacle being disposed slightly above the mouth of the inner receptacle.

3. A rotary ash sifting device, including a portable ash containing element in the form of a pail, a foraminous sifting receptacle disposed within the pail and rigidly 50 secured thereto adjacent the bottom thereof, said receptacle being open and spaced apart from the walls of the pail, at the top, and the same being of slightly less height than the pail, whereby the walls of the pail extend above the mouth of the receptacle.

4. A rotary ash sifting device including a portable ash containing element in the form of an upwardly flaring pail, a foraminous sifting receptacle centrally disposed 60 within the pail and rigidly secured thereto adjacent the bottom thereof, said receptacle at its lower end conforming substantially with the bottom of the pail and being increasingly spaced apart upwardly from the 65 side walls of the latter, and the mouth of the

receptacle being disposed measurably within and below the mouth of the pail.

5. A rotary ash sifting device including a portable ash containing element in the form of an upwardly flaring pail, a foraminous 70 cylindrical sifting receptacle centrally disposed within the pail and rigidly secured thereto adjacent the bottom thereof, said sifting member being of substantially the same diameter as the bottom of the pail, and being slightly of less longitudinal extent than the pail, whereby the mouth of the receptacle falls slightly below the mouth of the pail.

6. In a rotary ash sifting device, an ash 80 containing element comprising a pail having a foraminous centrally disposed cup-like sifting receptacle rigidly secured therein, said receptacle being spaced from the surrounding side walls of the pail to provide an intervening space for the reception of ashes sifting from the receptacle, and the mouth of the receptacle being disposed slightly below the mouth of the pail, and 85 means for mounting and rotating said element, on a substantially horizontal axis, said means including a closure of suitable form to bodily enter the pail and effect supporting engagement with the side walls of the latter adjacent the mouth thereof, and to 90 overlie and close the mouth of the receptacle while permitting ashes accumulating in said intervening space to be ejected from the mouth of the pail.

7. In a rotary sifting device, an ash containing element comprising a pail having a cup-like sifting receptacle therein; and means for removably mounting and rotating said element on a substantially horizontal axis, said means including a rotatably 100 mounted plate adapted to enter the mouth of the pail and overlie and close the mouth of the receptacle, and to effect supporting engagement with the side walls of the pail adjacent the mouth thereof, while leaving 105 portions of the area of the mouth of the pail uncovered for the ejection of ashes therefrom.

8. In a rotary ash sifting device, a rotatable ash containing and sifting element 115 having an open mouth, and means for removably mounting and rotating the element to sift the ashes, said means including a flat pivotally mounted closure and supporting plate adapted to enter, engage and partially 120 overlie the mouth of the element, said plate being of substantially rectangular outline and having peripheral edge reinforcements.

9. In a rotary ash sifting device, a rotatable ash containing and sifting element 125 having an open mouth, and means for removably mounting and rotating the element said means including a pivotally mounted plate of resilient material adapted to act as a closure and support for the mouth of 130

the element and to supply spring pressure for detachably locking and maintaining said element in rotative mounted position.

10. In a rotary ash sifting device, the combination with a lid for an ash can having a substantially flat top with a hooded recess therein, of means associated with the lid for removably mounting and rotating an ash containing and sifting element under the hood on an axis substantially in the plane of the flat portion of the lid, said means including a cross arm adapted to be removably disposed and locked transversely across said recess and likewise substantially 15 in the plane of the flat portion of the lid, said cross arm carrying a pivotally mounted member for engaging one end of said element.

11. In a rotary ash sifting device, the combination of a rotatable ash containing and sifting element and a mounting for removably supporting and rotating said element therein, of means for removably securing and locking said element in the mounting, said means including a cross arm carrying a pivoted member for engagement with one end of said element, said cross arm being hinged at one end to the mounting to permit both longitudinal and transverse 25 movement of the engaging member with respect to the element when the latter is seated in the mounting.

12. In a rotary ash sifting device, the combination of a rotatable ash containing and sifting element and a mounting for removably supporting and rotating said element therein, of means for removably securing and locking said element in the mounting, said means including a cross arm 35 with a transversely projecting pivot intermediately disposed on one side thereof for carrying a member for engagement with

one end of said element, said cross arm being hinged to the mounting at one end and being adapted to be detachably locked thereto at 45 its opposite end and a heel provided on the cross arm for abutment against the mounting to prevent torsional movement thereof due to the weight of the element on the pivot when the element is in locked position in the mounting.

13. In a rotary ash sifting device, the combination with an ash containing and sifting element in the form of a pail, of means for removably mounting and rotating said element in substantially horizontal axial position, said means comprising rotative clamping and supporting members adapted to be applied to the mouth and the bottom of the element, the member applicable to the bottom of the element consisting of a manually rotative plate adapted to effect supporting engagement therewith and to permit the transmission of rotary movement to the element through frictional contact with the bottom.

14. In a rotary ash sifting device, the combination with an ash sifting element in the form of a pail, of means for removably mounting and rotating said element in substantially horizontal axial position, said means comprising clamping and supporting members adapted to be applied to the mouth and bottom of the element, the member applicable to the bottom of the element consisting of a manually rotative flat plate adapted to enter the tine recess of the pail and to co-operate with the tine and the bottom thereof to effect supporting engagement with the element and to permit the 70 transmission of rotary movement thereto.

In testimony whereof, I affix my signature.

FRANK H. LEHMAN.
